UNITED STATES PATENT OFFICE.

WILLIAM A. PRINGLE, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO, CANADA.

MANIFOLDING BOOK.

Application filed November 15, 1924. Serial No. 750,023.

This invention relates to record sheets, strips and the like and with respect to its more specific features to the adaptation of such sheets and strips for filing or for cooperation with manifolding machines, especially autographic registers.

One object of the invention is the provision of a practical device of the character described having a weakened or tearing line which will not substantially interrupt the surface of the sheet nor thicken the sheet at the weakened line.

A further object is the provision of a strip, adapted to be fed in a manifolding autographic register or like machine, with a weakened line such that feed in the register without objectionable interference by the registering instrumentalities and without injuring the carbon transfer sheets, will be promoted.

A further object of the invention is to provide a practical pad of substantially uniform thickness throughout though composed of a great number of superposed sheets or leaves in which the weakened lines are also in approximately superposed relation.

A further object is to provide a sheet having a line of severance which when severed may have its edges brought together again without buckling.

A further object is to provide a sheet with a line of severance which because of its nature will be biased to fold in one direction.

A further object is to provide a pad adapted for use with automatic machinery such for example as manifolding machinery, having lines of severance in the successive sheets of such a character that the thickness of the pad will not be locally increased due to the line of severance.

In the construction of record sheets, it has been proposed to provide lines of weakness therein for the purpose of facilitating the tearing of the sheet before or after inscription for any one of a variety of purposes, as for example, it may be desired after inscription to tear a portion of the sheet from the remainder, to separate a record contained

thereon from the remainder of the record, or it may be desired, where filing apertures are used in a sheet to tear the sheet between the filing aperture and an adjacent edge to facilitate placing the filing aperture over a filing post from the side.

The methods of producing such line of weakness, however, have proved unsatisfactory for many purposes. For example, with the zigzag form of book comprising a plurality of strips interfolded zigzag to form a plurality of sets of record leaves, if the leaves contain lines of weakness which are thicker than the sheet, such as customarily results from perforating the paper at spaced intervals, and if such perforated lines be asymmetrically disposed the resultant greater thickness of the pad opposite the thickened line of weakness is of inconvenience in the pad and the fact that it is asymmetrically disposed is apt to interfere with the proper feeding of the sheets in registry.

Moreover, where such thickened lines of weakness pass over the edges of interposed carbon sheets, the projections hitherto due to the line of weakness engage and fray the carbon sheets.

Furthermore, when the line of weakness is formed by perforating the sheets at spaced intervals, not only is the appearance of the sheet marred, but the edges of the perforations project outside the surface and interfere with the carbon sheets employed.

It has heretofore been proposed to provide manifolding machine pads, comprising a plurality of sheets attached end to end in a continuous strip, with filing apertures in the separate sheets having openings entirely through the sheets connecting the filing apertures with the adjacent edges of the sheets. The operation of such sheets, however, in manifolding devices has not been satisfactory for the reason that the edges of the filing apertures are apt to engage and deface or tear the interposed carbon sheets.

By the present invention the foregoing difficulties and others are largely eliminated with consequent improvement in the con-

struction, and operation of sheets and pads as herein referred to.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawing, in which:

Figure 1 is a cross section of a sheet weakened in accordance with this invention, and for convenience it is illustrated as a section along the line 1—1 of Fig. 2;

Figs. 2, 3, 4, 5 and 6 are modified forms of sheets showing different ways in which the invention may be utilized; and

Fig. 7 is a diagrammatic perspective view of a pad and sheets embodying this invention.

The numeral 3 designates a sheet, or strip, of paper which, as illustrated in Fig. 1, is magnified many fold, more clearly to illustrate the manner of weakening. For manifold purposes the sheet 3 will be of thin, soft paper. At the point to be weakened, the sheet 30 is slit at 2 being cut from one face of the paper part way through to the other side but not entirely through the sheet. This provides a line of weakness, or severance, along which the sheet may readily be torn. The slitting 35 may be conveniently done by a rotary knife which should be kept sufficiently sharp so that the fibers of part of the thickness of the sheet are severed without burring. Thus, the edges of the slit will lie side by side without thickening the sheet at the line of weakness. Furthermore, in order to prevent raising the opposite face of the sheet directly opposite the slit, and to maintain said opposite face flat and flush with the adjacent surface. 40 of the sheet, said opposite face should be preferably firmly backed by a smooth platen during the slitting. In this way the material of the sheet directly opposite the slit will be continuous cross-wise of the slit and flat 45 and flush with the adjacent surface.

The edges of the slit can be made to lie close together or appreciably separate as desired, by flexing the sheet while it is cut, either toward or away from the cutting edge.

In Figs. 2, 3, 4, and 5, there is shown the application of this invention to record sheets having apertures, as filing apertures, therein where it is desired to make a weakened connection, or line, between the filing aperture 60 and an adjacent edge of the sheet. Thus, in a sheet 3 of Fig. 2, there are provided filing apertures 4 extending entirely through the sheet adjacent one edge thereof, while a weakened line 5, leading from the aperture 4 to the

adjacent edge 6 of the sheet, may be formed 65 by slitting the sheet half way through as before described. In this figure, the weakened line connects the nearest edge of the filing aperture 4 with the adjacent edge of the sheet. In the form illustrated in Fig. 3, the filing 70 aperture 7 is connected to the adjacent edge of the sheet 8 by cutting half way through the sheet on two substantially parallel lines 9 and 10.

As illustrated in Fig. 4, a line may be half 75 cut through the sheet as shown at 11, slanting toward the edge of the sheet from the perforation. In the form illustrated in Fig. 5, the weakened line 18 may extend between the filing aperture and the edge of the sheet, but 80 with an unsevered portion 19 or 20 at one or both ends thereof.

With these constructions by reason of the fact that the sheet is cut part way through, when it is completely severed for placing 85 upon filing pins, the edges of the sheet at the line of severance will lie side by side without buckling, since the fibers at this point are cut and hence there is no jagged line of fibers 90 which do not fit smoothly together.

In Fig. 6, the invention is illustrated as applied to a sheet in which it is desired to sever one portion of the sheet from the remainder after inscription. To this end, a weakened line 21 may be provided separating 95 such portion of the sheet from the remainder by cutting the sheet halfway through as before described between the two portions. Thus, for example, if it be desired to have a sheet containing a portion giving the price 100 and a second portion giving the cost, such sheet may pass through one department, intact, and thereafter the portion of the sheet bearing the cost may be removed by tearing 105 along the weakened line, and the remainder transmitted to another department.

With the form of weakening described it will be seen that the sheets will fold more readily in the direction to open the slit than in the reverse direction. Hence, the sheet 110 will have a definite bias at the fold.

An important feature of the invention relates to the pad which may be formed. Because the superposed sheets of which the pad is composed are weakened in the manner hereinbefore explained, the pad will not bulge due to the presence of weakened lines, as is the case where the sheets are weakened by perforating, and as is especially noticeable in pads wherein weakened lines are directly superposed. This aspect of the invention is especially noticeable and particularly advantageous in the form of pad illustrated in Fig. 7, in which a plurality of long, thin, soft, paper runner strips are folded zigzag, the 115 folds of one strip being interengaged with those of the others so as to provide superposed sets of superposed record leaves 120 125

nected end-to-end. Where such a pad is designed for use with the feed mechanism intended to be controlled by the strips to bring the printed forms into accurate registry, 5 each of the sheets may be provided with a longitudinal series of punch openings, or feed control apertures, as for example, 23, wholly through the strip near one end of each set of forms and with supplemental lines of 10 weakness 24 leading from the feed control apertures 23 to the transverse lines of weakness 25, at the fold lines, along which latter lines the strips may be parted at different 15 points in their lengths. By reason of the fact that the weakened lines 24 and 25 are made by slitting part way through the strips, as hereinbefore set forth, no thickening of the pad will result due to relative location of these lines in the pad, and hence the sheets 20 will lie flat in the package and will feed through the mechanism symmetrically, and without injury to themselves or the delicate elements of the machine.

It will be observed that as the strips of 25 the pad of Fig. 7 are fed in a manifolding machine, the supplemental lines 24, advance lengthwise and being straight, there is practically no tendency for their edges to catch in the machine or for the edges of the carbon 30 strips of the machine to catch in these supplemental lines.

Where the invention is used as a line of separation between successive sheets of a continuous strip, the form of weakening employed will facilitate folding the strip between the sheets. When, moreover, the cutting, or slitting, be performed alternately on 35 different sides of the sheet, it will be seen that the sheet will be biased by the cutting 40 to fold zigzag in a definite manner, since it is easier for the partially severed sheet to fold in a direction to open the cut or slit than in the opposite direction.

The lines of weakness herein referred to 45 may be made by a slit or line of severance, as before described, which is continuous longitudinally of the line, or by a series of separate slits or cuts partway through the sheet and relatively closely following each other along the line. In the latter instance unslit- 50 ted sheet material extends across the line and strengthens the connection without impairing the utility as a tearing line.

Since certain changes may be made in the 55 above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the inven-

tion herein described, and all statements of 65 the scope of the invention which, as a matter of language, might be said to fall therebetween.

Having described my invention, what I claim as new and desire to secure by Letters 70 Patent, is:—

1. A soft thin sheet of paper slit partway but not entirely therethrough from one face to form a line of weakness in the sheet, said sheet having an aperture wholly there- 75 through to which said line of weakness leads.

2. A soft thin sheet of paper slit partway but not entirely therethrough from one face to form a line of weakness in the sheet, the opposite face of said sheet at said weakened 80 line being flat and flush with the adjacent surface of the sheet, said sheet having an aperture wholly therethrough to which said line of weakness leads.

3. A long runner strip of soft thin paper 85 having a longitudinal series of feed control apertures punched wholly therethrough, transverse lines of weakness along which the strip may be parted at different points in its length, and supplementary lines of weakness 90 leading from said transverse lines to said apertures, respectively.

4. A long runner strip of soft thin paper having a longitudinal series of feed control apertures punched wholly therethrough, 95 transverse lines of weakness along which the strip may be parted at different points in its length, and supplementary lines of weakness leading from said transverse lines to said apertures, respectively, said strip having slits 100 partway but not entirely therethrough, from one face, forming said supplementary lines of weakness, the opposite face of said strip at said supplementary lines being flat and flush with the adjacent surface of the strip. 105

5. A long runner strip of soft thin paper having transverse lines of weakness and a longitudinal series of feed control apertures punched wholly therethrough and strip weakening slits in one face leading from said 110 transverse lines to said apertures, respectively, the material of said strip directly opposite said slits being continuous crosswise of said slits and flat and flush with the adjacent surface of the strip.

6. A soft thin paper sheet having a punch opening wholly therethrough, and a line of weakness extending toward said opening, the thickness of the sheet being slit partway but not wholly therethrough to provide said line. 120

7. A pad composed of a plurality of long, soft, thin paper record strips folded zig-zag, the folds of one strip interengaged with those of the others so as to provide superposed sets of superposed leaves connected end to end, 125 each strip having a line of weakness at its fold line, said line in one of said strips being provided by a slit, or slits, partway but not

entirely through the strip from one face, each of said leaves having an aperture wholly therethrough and a supplementary line of weakness leading from said aperture toward

5 an edge of the leaf.

8. A record strip containing a succession of sales record forms and a line of severance

between each set of said forms, formed by a cut extending partway through from one face to the other, successive lines of severance being cut from alternate sides, whereby the sheet is biased to refold zigzag. ¹⁰

In testimony whereof I affix my signature.

WILLIAM A. PRINGLE.
